UNITED STATES PATENT OFFICE.

EDWIN ROSS, OF NEW YORK, N. Y.

DESIGN FOR A BOTTLE.

Application filed April 11, 1925. Serial No. 13,093. Term of patent 14 years.

To all whom it may concern:

Be it known that I, EDWIN Ross, a citizen of the United States, residing at New York city, county of New York, borough of Manhattan, and State of New York, have invented a new, original, and ornamental Design for Bottles, of which the following is a specification, reference being had to the accompanying drawing, forming part thereof.

I claim:—

The ornamental design for a bottle as shown.

EDWIN ROSS.
